NECKTIE RACK

Abraham I. Zimmer, Fairfield, Conn.

Application August 24, 1949, Serial No. 4,671

Term of patent 14 years

(Cl. D33—8)

To all whom it may concern:

Be it known that I, Abraham I. Zimmer, a citizen of the United States, residing at Fairfield, in the county of Fairfield and State of Connecticut, have invented a new, original, and ornamental Design for Necktie Rack, of which the following is a specification, reference being had to the accompanying drawing, forming a part hereof.

Fig. 1 is a front elevational view of a necktie rack, showing my new design;

Fig. 2 is a top plan view of the same; and

Fig. 3 is a side elevational view of the same.

I claim:

The ornamental design for a necktie rack, substantially as shown.

ABRAHAM I. ZIMMER,
